UNITED STATES PATENT OFFICE

CHARLES C. CHINSKI, OF BEAUMONT, TEXAS

CHANGEABLE ADVERTISING DEVICE

Application filed May 14, 1929. Serial No. 363,013.

This invention relates to a changeable advertising and display apparatus operable by a wind vane to move certain parts of an advertising panel successively into a predetermined display position on a bill-board or the like adapted for use on public highways.

The main object of the invention is to provide a device of the character described, which is operable by the rotation of a wind vane to move an advertising panel successively from one of several predetermined display positions relative to a fixed display opening in the bill-board or the like.

Other objects of the invention will become apparent as the detailed description thereof proceeds.

In the drawings—

Fig. 1 is a perspective of the invention as applied to a bill-board or the like;

Fig. 2 is a rear elevation of the invention, with parts of two guide rails broken away to show details of construction;

Fig. 3 is a horizontal section on the line 3—3 of Fig. 2;

Fig. 4 is a horizontal section on the line 4—4 of Fig. 2;

Fig. 5 is a horizontal section on the line 5—5 of Fig. 2;

Fig. 6 is a fragmentary horizontal section, to an enlarged scale, of the operating parts shown at the right-hand end of Fig. 5;

Fig. 7 is a side elevation of the parts shown in Fig. 6;

Fig. 8 is a vertical section taken on the line 8—8 of Fig. 2, the scale being enlarged; and

Fig. 9 is a perspective view of a cam plate forming part of this invention.

In the drawings the invention is shown as a structure comprising a pair of standards 1 and 2, connected by a base 3 and a top rail 4; all framed together to support a panel board 5 adapted to receive adver-

tising matter and provided at its center with a display aperture 6.

The back of the panel board 5, (Fig. 2), has a pair of angle irons 7 and 8 fixed thereto to form guideways for slidably supporting and guiding a panel 9, which, as shown in Fig. 1, is divided into three sections 10, 11 and 12, each of which is equal in area and outline to the display aperture 6; and each of which is designed to have advertising matter displayed thereon.

In order to move the panel 8 so as to cause the sections 10, 11 and 12 to appear fully and successively at the display opening 6, the panel 9 has a pair of angle iron brackets 13 and 14 secured to opposite ends of the back thereof and adapted to be engaged by cam hooks pivotally secured in certain positions on the endless sprocket chains 17 and 18. In order to move these chains in opposite directions past the back of panel 9, a pair of vertically disposed shafts 19 and 20 are rotatably mounted in bearings 21—22—23 and 24—25—26, respectively, suitable secured to the back of the standards 1 and 2, respectively.

The bearings 21 and 24 are step bearings in which the lower ends of shafts 19 and 20 are supported rotatably and the bearings 22—23 and 25—26 are spaced apart to receive grooved pulleys 27 and 28 fixed to shafts 19 and 20, respectively. These pulleys 27 and 28 are rotated in opposite directions by cables 30 and 31, respectively, extending around the double grooved pulley 32 which is fixed to a shaft 33 supported rotatably in bearings 34 and 35 fixed to the back of the top rail 4, the cable 31 being crossed to ensure rotation of shaft 20 in the opposite direction to the direction of rotation of shaft 19. A wind vane V of any suitable construction or type is fixed to the upper part of shaft 33 in order to rotate said shaft.

The sprocket chain 17 is rotated by the

sprocket wheels 36 and 37, of which the wheel 36 is fixed to shaft 19, and wheel 37 is rotatably mounted on shaft 20 between the sleeves 38 and 39. The chain 18 is rotated by sprocket wheels 40 and 41 of which the wheel 40 is rotatably mounted on shaft 19, and the wheel 41 is fixed to shaft 20 to rotate therewith. This construction, obviously, ensures that the chains 17 and 18 will move in opposite directions past the back of the panel 9 regardless of the direction of rotation of shaft 33 by the wind vane V.

The chain 17 moves horizontally past the back of panel 9 and centered between the upper and lower ends of the angle iron 13. A hook member 42 is pivoted on the upper edge of the chain 17 and a similar member 43 is pivoted to the lower edge of said chain 17. These members 42 and 43 are shaped symmetrically about their pivot axes in order to adapt them for sliding in either direction along guideways 44 and 45 formed on a cam plate 46 having one end bifurcated and the furcations thereof bent around shaft 19 on opposite sides of the wheel 36.

At one end of the bill-board, the cam plate 46 is supported by strap brackets 47 and 48 extending between the stretches of the sprocket chains 17 and 18 and suitably secured to the back of the panel board 5; and is formed with two contact surfaces 49 and 50 of different lengths. The upper surface 49 is adapted to contact with either edge of the hook member 42 and keep it in moving contact with the angle iron 13 for the full length of the contact surface 49. The length of surface 49 is substantially equal in length to the width of each of the sections 10, 11 and 12, and surface 50 is twice this length, in order to effect the movement of panel 9 necessary to locate the sections properly in the display aperture 6.

At the other end of the bill-board, a cam plate 51, formed to pair with the cam plate 46, is supported by strap brackets 52 and 53, extending also between the stretches of the sprocket chains 17 and 18 and suitably secured to the back of the panel board 5. This plate 51 is formed with two contact surfaces 54 and 55 of different lengths, the length of surface 55 being equal to the width of each of the sections 10, 11 and 12, while the length of surface 54 is equal to twice this width, in order to effect proper successive movements of the display panel 9 relative to the opening 6.

The upper surface 54 is adapted to contact with either edge of the hook member 56 pivoted to the upper edge of the chain 18; while the lower contact surface 55 is adapted to contact with the hook member 57 pivoted to the lower edge of the chain 18. These hook members are symmetrically shaped relative to their pivot axes in order to adapt them for sliding contact in either

direction on the contact surfaces of the plate 51.

The spacings between the hook members 42 and 43 on chain 17, and between members 56 and 57 on chain 18 determine the intervals between successive movements of the display panel 9 at any given speed of rotation of the wind vane V. As shown in the drawings, these spaces are each equal to one-fourth of the entire length of each of the chains. Obviously, the distance between the shafts 19 and 20 must at least be equal to five times the width of each section 10, 11 and 12, where there are only three sections, and these shafts must be equidistantly spaced from the center of the aperture 6.

While I have shown a display panel provided with only three display sections, the invention must not be considered as limited in anyway to this number, as it obviously involves nothing more than the ordinary skill of the mechanics to design a board having any desired number of display sections and operated by mechanism similar in principle of operation to that disclosed.

It will be noted that each of the contact plates 46 and 51 has its wide end bifurcated and bent around the shafts 19 and 20, respectively, with the furcations arranged on opposite sides of the sprockets 36 and 41, respectively. While this construction is not actually necessary to the operation of the device, it does afford a supporting means to prevent lengthwise movements of the plates 46 and 51 on the back of the board.

The display panel 9 is provided on its bottom edge with ball casters 58, 59 and 60, equidistantly spaced apart to seat in three of the correspondingly spaced recesses 61, 62, 63, 64 and 65. These recesses hold the panel board 9 yieldingly fixed in any of its three positions during the intervals when it is not being moved by the hook members 42 and 43 or 56 and 57. Of course, any desired number of casters may be used providing the number of recesses be increased or decreased to take care of the proper positioning of the display panel 9.

A casing 66 may be detachably secured to the back of the device in order to protect the apparatus from the elements.

In operation: When the shaft 33 is rotated in either direction by the action of wind on the vane V, it is obvious that the shaft 19 will be rotated by cable 30 in the same direction; and shaft 20 will be rotated in the opposite direction by cable 31.

Referring now to Fig. 4, where the panel 9 is shown with the section 11 centered in the display aperture 6 and with the hook member 43 just engaging the angle iron bracket 13 in order to move panel 9 with the display section 12 into display position in the aperture 6. As soon as angle iron 13 reached its dotted line position indicated

in Fig. 4, the hook member 43 reaches the end of contact surface 50 and swings back to dotted line position. The panel 9 now is positioned as shown in Fig. 5 and chain continues to rotate without moving the panel 9 because the channel iron 13 is clear of the cam plate 46. However, the angle iron 14 is located in front of cam plate 51, and the hook member 56, riding on cam surface 54, engages channel iron 14 to move the panel toward the display opening 6; and the hook 57 afterwards moves the panel from center position to the extreme left of the board. The cam hooks on the chains 17 and 18 operate successively on the angle irons 13 and 14 to move the panel 9 intermittently and through predetermined distances for the successive display of the sections 10, 11 and 12 of the display panel 9 before the display aperture 6.

Since the cam hooks 42, 43, 56 and 57 are symmetrically shaped, it is obviously immaterial which direction the shaft 33 is rotated by the wind. The display panel is reciprocated back of the aperture 6 by the successive operation of the two chains 17 and 18 which rotate continuously in opposite directions.

It will be obvious from the disclosure herein that I have provided a novel changeable advertising exhibitor which involves no expense for operating power, and which can be very easily and cheaply manufactured.

What I claim is:

1. An advertising device comprising a board having a display aperture, a panel slidable on the back of said board across said aperture, a wind operated shaft, and means connecting said shaft to said panel to reciprocate said panel successively into predetermined positions relative to said aperture.

2. An advertising device comprising a board having a display aperture, a panel divided into a plurality of sections of substantially the same shape and area as said aperture, a wind operated shaft, a pair of shafts supported on said board parallel to each other, means connecting said pair of shafts to said wind operated shaft to cause rotation of said pair of shafts in opposite directions, and means connecting said shaft to said panel to reciprocate said panel in successive steps to expose one of its sections completely by said aperture.

3. An advertising device comprising a board having a display aperture, a display panel reciprocable on the back of said board across said aperture, means for intermittently moving said panel in one direction past said aperture, and means for intermittently moving said panel in the opposite direction across said aperture.

4. An advertising device comprising a board having a display aperture, a display

panel reciprocable on the back of said board across said aperture, means for intermittently moving said panel in one direction through equal distances to a predetermined position relative to said aperture, and means for intermittently moving said panel in the opposite direction from said predetermined position through equal distances to another predetermined position relative to said aperture.

5. An advertising device comprising a board having a display aperture, a display panel reciprocable on the back of said board across said aperture, a wind driven shaft, a pair of countershafts, means connecting said wind driven shaft to said countershafts for rotating said shafts in opposite directions, a pair of endless chains extending across the back of said panel and rotated in opposite directions by said countershafts, and cooperating means on said chains and the back of said panel for reciprocating said panel by successive equal steps from one predetermined position to another relative to said aperture.

6. An advertising device comprising a board having a display aperture, a display panel reciprocable on the back of said board across said aperture, a pair of shafts rotatably mounted parallel to each other on said device, means for rotating said shafts in opposite directions, and cooperating means on said shafts and said panel for reciprocating said panel by successive equal steps past said aperture.

7. An advertising device comprising a board having a display aperture, a display panel reciprocable on the back of said board across said aperture, a pair of shafts rotatable in opposite directions on said device, a pair of endless chains extending around said shafts and movable in opposite directions by said shafts along the back of said panel, a stop on said panel located in the path of movement of one of said chains, means on said chain engageable with said stop for moving said panel through equal distances in one direction past said aperture, a second stop, and means on the other of said chains and engageable with the second stop for moving said panel through equal distances in the opposite direction past said aperture.

8. An advertising device comprising a board having a display aperture, a display panel reciprocable on the back of said board across said aperture, a pair of shafts rotatable in opposite directions on said device, means for rotating said shafts, and means on said shafts engageable with said panel for reciprocating said panel by successive equal steps in opposite directions relative to said aperture.

9. An advertising device comprising a board having a display aperture, a display

panel reciprocable on the back of said board across said aperture and having display sections equal in area to said aperture, means for slidably supporting said panel on the back of said board, means for yieldingly locking said panel in predetermined positions to position the panel with one section at a time behind said aperture, and wind operated means for moving said panel in opposite directions from one locked position to another.

In testimony whereof I affix my signature.
CHARLES C. CHINSKI.
